UNITED STATES PATENT OFFICE.

ORSON F. KIRKPATRICK, OF NORTH ENGLISH, IOWA.

AIR-BRAKE COUPLING.

1,153,318.

Specification of Letters Patent. Patented Sept. 14, 1915.

Application filed January 13, 1915. Serial No. 2,057.

To all whom it may concern:

Be it known that I, ORSON F. KIRKPATRICK, a citizen of the United States, residing at North English, in the county of Iowa and State of Iowa, have invented certain new and useful Improvements in Air-Brake Couplings; and I do hereby declare the following to be a full, clear, and exact description of the invention, such as will enable others skilled in the art to which it appertains to make and use the same.

This invention relates to air-brakes used on railway trains, more especially freight trains, and the object of the invention is to provide means for automatically coupling the air-pipes with which such air-brakes are supplied.

The invention is fully disclosed in the description and claims following, reference being had to the accompanying drawing, in which—

Figure 1 is a side view, partly in section, illustrating my invention as in use. Fig. 2 is a mid-sectional plan view of the same. Fig. 3 is an end view illustrating the mounting or cage for the coupling-bar, shown in section.

Referring to the drawing, 1 denotes the under frame of a car, below which is mounted in the usual way the regular car-coupling 2, suitably supported as by a yoke 3. Directly beneath the car-coupling is mounted the air-coupling, which is the subject of this invention.

The coupling comprises a pair of engaging heads or coupling-bars, of which one is supposed to be attached to the car at each end. The main body of the bar is tubular, and on its reduced rear end portion 4 is mounted a spring 5 compressible between the shoulder 6 and the abutment 7. An angular plate 8 at the rear end prevents the bar from turning and limits its forward movement. The main body of the bar 9 is mounted in a cage which may be suspended from the yoke 3, and comprises a rectangular frame 10, cross-bars or plates 11 and 12 slidable in the frame, and springs 13 between the plates and the inner sides of the frame. It will be seen that the outer ends of the plates 11 are forked at 14, and the other plates, 12, have terminal tongues 15 passing through the forks transversely, the effect of which construction is to permit the coupling-bar to move in any desired direction, up, down, or to either side, a limited

distance. The holding-plates are held slidably in the cage, as by ribs 26 engaging the forked plates, the other plates being held by the forked ones. The abutment is most conveniently attached directly to the cage, as by a tail-piece 27, but may be otherwise mounted if desired. Normally, as will be evident, the bar is held centrally, and as best shown in Fig. 3. This freedom of movement is made necessary by the fact that the pair of coupling heads when engaged are rigid, and the interlocked pair must swing sidewise when the cars go around curves, and must yield vertically when cars of different height are coupled, or when the cars vary vertically, from any other reason. To allow for this swing of the coupling-bar it is rather loosely mounted in the abutment, as shown.

The engaging heads are inclined at 16, and provided with a partially encircling and flared hood 17, which serves as a bell-mouthed guide for the end of the companion coupling. This end is formed as a terminal tongue 18, which in coupling position enters a socket 19. When so interlocked, as shown in Fig. 2, the parts are brought to exact position, and the packing-rings 20 at the air terminals are brought snugly and properly together. Ordinarily they will so remain until the cars are uncoupled, with no other aid than the end pressure of the springs 5, but to guard against contingencies provision is made for locking them in this position. A simple device for this purpose is a latch or hook 21 pivoted on each coupler-bar at 22, and engaging a notch 23 in the tongue of the companion coupling. In coupling, the respective heads are pushed back considerably, as shown in Fig. 1, correspondingly compressing the springs 5. This allows for the use of a slack chain 24 connecting with an arm 25 of the hook and some fixed part, as the cage, to disengage the hook when the cars are uncoupled, in a manner so simple as to require no description.

In practice the tongues 18 are made with straight sides practically parallel with the sides of the body of the coupling-head, and when in final position project at some length into the socket in the companion head. The effect of this is to completely lock the two heads together sidewise, so that in turning around curves the two heads are held rigidly in line, regardless of the latch or the compression springs, and a partial failure on

the part of either to act would not necessarily create a leak of air at the joint.

To the rear end of the coupling-bar is attached a section of air-hose, the opposite end of which is supposed to connect similarly with another coupling at the other end of the car.

Having thus described my invention, I claim:

- 10 1. An air-brake coupling, comprising a centrally tubular body adapted to connect at its inner end with an air-hose, a sidewise and vertically yielding mounting therefor permitting endwise slide of said body, a spring coöoperating with the coupling body to force it outwardly, a laterally inclined head with a centrally disposed air-hole and a yielding packing therefor, the head being extended to form a straight-sided terminal tongue, a bell-mouthed guiding hood terminating in a socket for the tongue of a companion head, and means to prevent the axial turning of said head.
- 15
- 20

2. An air-brake coupling, comprising a centrally tubular body adapted to connect at its inner end with an air-hose, a yielding mounting therefor permitting the body to move endwise a limited distance, means adapted to prevent its turning axially, a spring coöoperating with the body to force it outwardly, a laterally inclined head with a centrally disposed air-hole and a yielding packing therefor, the head being extended to form a straight-sided tongue, a flaring hood terminating in a tongue-receiving socket, a latch engaging the tongue when in coupled position, and a slack chain connecting the latch with some fixed portion of the apparatus, and operating to release the latch by the take-up of the slack. 40

In testimony whereof I affix my signature in presence of two witnesses.

ORSON F. KIRKPATRICK.
